DOOR OPENING MECHANISM

Robert Haslam, Philadelphia, Pa.

Application November 8, 1938, Serial No. 239,525

12 Claims. (Cl. 268—36)

This invention relates to door opening mechanisms. It has for its objects the production of a device of this class which will be positive in its operation both in opening and closing the door and which will nevertheless be comparatively simple in structure.

For the purpose of illustrating my invention, I have disclosed in the drawings which form a part hereof, and will now describe two of the many possible embodiments of my invention.

In said drawings,

Figure 1 is a perspective view of my novel structure attached to a door. A portion of the tread-plate 6 has been broken away for the purpose of showing otherwise hidden parts. The full lines show the position of the respective elements when the door is closed and the dot and dash lines show the position of the arm and cable when the door is opened.

Figure 2 is a plan view of the door actuating portion of my novel mechanism with the casing removed, taken along the lines 2—2 of Figure 1.

Figure 3 is a front view of the disclosure in Figure 2.

Figure 4 is an end view of the disclosure in Figure 2 taken along the line 4—4 of said figure.

Figure 5 is a plan view of the tread portion of my mechanism.

Figure 6 is a section taken along the line 6—6 of Figure 5.

Figure 7 is a section taken along the line 7—7 of Figure 5.

Figure 8 is a section of a fragment taken along the line 8—8 of Figure 5.

Figure 9 is a section of a fragment taken along the line 9—9 of Figure 5.

Figure 10 is a section of a fragment taken along the line 10—10 of Figure 5.

Figure 11 is a section of a fragment taken along the line 11—11 of Figure 5.

Figures 12 and 13 are schematic plan views of the door actuating portion of the mechanism taken along the line 2—2 of Figure 1. The full and dotted lines in Figure 12 show the respective positions of the respective elements when the door is closed, while the dot and dash lines in this figure show the positions to which these elements have moved just after a person has stepped upon the tread-plate.

The full and dotted lines in Figure 13 show the positions of the respective elements of the door actuating mechanism when the door is fully opened, and the dot and dash lines in Figure 13 show the positions to which these elements have moved just after a person has stepped off the

tread-plate. A portion of the door intermediate its ends has been broken away to permit the showing of the remaining parts on as large a scale as possible.

5 Figure 14 is a plan view of a modification of the door actuating portion of my mechanism with the casing removed.

Figure 15 is a front view taken along the line 15—15 of Figure 14.

10 Figure 16 (see Sheet 2 of the drawings) is a section taken along the line 16—16 of Figure 2.

Figure 17 (see Sheet 4 of the drawings) is an enlarged section of a fragment taken along the line 17—17 of Figure 5. The full lines show the 15 positions which the pin and tread-plate occupy before the tread-plate has been adjusted, and the dot and dash lines show the position which each of these elements assumes after the tread-plate has been adjusted.

20 Referring more particularly to the drawings wherein similar reference numerals denote similar parts, reference numeral 1 denotes my door opening device as a unit. The unit 1 consists of the tread portion 2, the transmitting portion 3, and the door actuating portion 4.

The tread portion 2 consists of a frame 5, a tread-plate 6 pivoted with reference to said frame at 7, and an arm 8 which is actuated in a horizontal plane about a pivot 9 by the movement of 30 said tread-plate 6.

The frame 5 is rectangular in shape and comprises the walls 10, 11, 12, and 13. The walls 10, 11, 12, and 13 have, respectively, the sloping outer surfaces 14, 15, 16, and 17 and the vertical surfaces 18, 19, 20, and 21. The walls 10, 11, 12, and 13 have formed therein the apertures 22 through which extend suitable bolts 23 which fasten the frame 5 to the floor 24.

Each of the walls 11 and 13 (see Figures 5 and 40 17) has formed therein an internally threaded aperture 26 which receives a suitably threaded pin 27. Each pin 27 terminates in a non-threaded portion 28 which extends into and is received in a suitable bore 30 formed in the boss 29 which is formed on the tread-plate 6. Each threaded pin 27 has mounted thereon near the outer end thereof the washer 25 and the locknut 31. The non-threaded portion 28 of the pin 27 serves as a pivot 7 for the tread-plate 6. The

45 threaded pins 27 also serve as a means for laterally adjusting the tread-plate 6. The locknut 31 serves to lock the threaded pin 27 in any desired position.

50 A shoe 32 is formed in each of the front corners of the frame 5. Each shoe 32 has a recess 33

formed therein which serves as a seat for the lower end 36 of the spring 34. The upper end 35 of the spring contacts the inner surface 37 of the tread-plate 6 and serves to keep the tread-plate in the raised or normal position shown in the drawings.

The wall 12 has a cut-out 38 formed therein centrally thereof which receives the arms 40 of the bearing plate 39. Each of the arms 40 has suitable apertures formed therein through each of which a screw 41 extends. This screw 41 attaches the arms 40 of the bearing plate 39 to the wall 12 of the frame 5.

The bearing plate 39 has formed therein the cut-out 42 through which a portion of the wedge 43 may extend when the tread-plate 6 moves downwardly. A roller 44 is carried by the bearing plate 39 and is positioned for contacting the surface 45 of the wedge 43. The surface 46 of the wedge 43 contacts a roller 47 which is suitably positioned in the arm 8. The arm 8 also carries a roller 48 which is suitably positioned for contacting the surface 50 of the wedge 49 which extends downwardly from the under surface 37 of the tread-plate 6. The wedges 43 and 49 act as a couple to cause the arm 8 to rotate about its pivot 9 from its full line position shown in Figure 1 towards its dot and dash line position in said figure whenever force is exerted upon the tread-plate 6 in the direction indicated by the arrow A in Figure 7.

The bearing plate 39 has attached thereto by means of suitable screws the bar 139, the lower surface of which rests upon the floor 24 thereby furnishing additional support to the outer end of the bearing plate 39. This construction permits the plate 39 to be raised a distance above the floor 24 sufficient to permit the wedges 43 and 49 to be depressed to their lowest respective points without touching the floor. It therefore becomes unnecessary to either make depressions in or to cut holes in the floor 24.

The bearing plate 39 has attached thereto by means of suitable rivets the arm 140 which in turn has threadably mounted therein the bolt 51. The end 52 of the bolt 51 contacts the face 53 of the arm 8 and acts as a stop to limit the motion of the arm 8 in the direction of the arrow B in Figure 1.

The arm 8 has formed therein a series of threaded apertures 54 any one of which receives the bolt 55 which extends through a suitable eye formed in the lower end of the cable 56 and serves to attach the cable 56 to said arm 8.

The cable 56 extends from the arm 8 through a suitable aperture 57 formed in the wall 10 of the frame 5, around a pulley 58 mounted in the lower end of the hollow standard 59, up through the standard 59, around a pulley 60 mounted in the upper end of the standard 59 and is connected at its upper end to one of the ends 75 of the lever arm 74 of the door actuating portion 4. The standard 59 is held in position by inserting its lower end in the bore 61 formed in the frame 5 and by anchoring its upper end to the door jamb 62 and the bracket 64 by means of the strap 63. The elements described in this paragraph together comprise the transmitting portion 3 of my novel unit 1.

The bracket 64 not only serves as a point of attachment for the strap 63 but it also serves as a support for one of the ends 66 of the plate 65 which serves as the bearing member of the door actuating portion 4. The other end 67 of the plate 65 is attached to a bracket 68 which in

turn has attached thereto one of the ends 70 of a turnbuckle cable 69. The other end 71 of the turnbuckle cable 69 is attached to a suitable hook 72 imbedded in the lintel 73. The turnbuckle cable 69 makes it possible to readily level off the door actuating portion 4 and to compensate for sagging which may occur from time to time either in the door frame or other elements of the building to which the door opening device may be attached.

The other of the ends 76 of the lever arm 74 is fixedly attached to the shaft 77 which is carried by the bearing plate 65. The shaft 77 also has fixedly attached thereto the gear 78 which meshes with a gear 79 fixedly attached to the shaft 81 which is also carried by the bearing plate 65. The shaft 81 has fixedly attached thereto the gear 80 which is positioned below the gear 79. The gear 80 meshes with the rack 82. The rack 82 is carried by an arm 83 which in turn is fixedly attached to one of the ends 85 of the cam band 84. The other of the ends 86 of the cam band 84 is pivoted on a shaft 87 which is carried by the bearing plate 65. The cam band 84 passes between the rollers 91 and 92 carried by the arms 89 and 90 of the lever 88. The lever 88 is pivoted on a suitable shaft 93 carried by the bearing plate 65 and, in addition to the arms 89 and 90, also has the arm 94 which terminates in a socket member 95. This socket member 95 has formed therein a suitable bore which receives the pin 96 which extends downwardly from the collar 97. The collar 97 encompasses the arm 99 of the lever 98 and is slidable thereon. The lever 98 is pivoted at one of its ends 100 upon the shaft 101 carried by the plate 65 and has depending therefrom near the other of its ends 102 the socket pin 104. The end 102 of the lever 98 is forked and has mounted therein the roller 103. The socket pin 104 has a suitable bore formed therein which receives the pin 106 which extends upwardly from the collar 105 which is slidably mounted on the bar 107. The bar 107 is attached at its ends 108 and 109 to the door 110 which is to be actuated. The bar 107 has fixedly attached thereto near its end 109 the collar 111. This collar serves as a bearing surface for one of the ends 113 of the spring 112 which is also mounted on the bar 107. The other end 114 of the spring 112 is attached to the collar 115 which is slidably mounted on the bar 107. The collar 115 contacts the collar 113 at a certain point in the swing of the door from its closed to its open position causing said collar to move and compress the spring 112. This in turn serves as a retarder and shock absorber with reference to the movement of the door to said position.

The free end of the arm 90 of the lever 88 has attached thereto one of the ends 117 of the shock absorbing unit 116. The other end 118 of the unit 116 is pivoted on the pin 119 carried by the plate 65.

The cam band 84 has extending therefrom the arm 120, the hook 121 of which serves as a point of attachment for the end 123 of the spring 122. The other end 124 of the spring 122 is attached to a hook 127 extending from a post 126 carried by the tensioning block 125. The tensioning block 125 is mounted in suitable channels formed in the angles 128—128 attached to the plate 65 for movement in a horizontal plane. The tensioning block 125 is held in any desired position in the slideway 129 by the pressure of the bolt 130 which is rotatably mounted in a suitable box 131 carried by the plate 65. The strength of the

spring 122 is such that it will overcome the inertia of the door 110 against movement, the frictional force of the door 110 upon its hinges and the frictional forces in the door actuating mechanisms 4, so that in the absence of a counter-acting force or forces which may be exerted upon the door 110 as a result of a pull upon the cable 56 the force of the spring 122 will be sufficient to cause the door 110 to close and keep it closed. Whenever it is desired to increase the force exerted by the spring 122 on the arm 120 it is only necessary to advance the bolt 130 in the direction of the arrow Z in Figure 4.

It is to be noted that the first act in mounting the tread-plate 6 in the frame 5 is the positioning of said tread-plate upon its pivots 7. When this is accomplished it often happens that the wedge 43 is not in the position shown in Figures 5 and 6 where the face 45 of said wedge contacts the roller 44. Instead, this face is at a point either to the right or left of said roller. To properly position said wedge it is only necessary to advance the pins 17 in the direction and through the distance which the wedge 43 must be moved in order to bring it to the position shown in Figures 5 and 6. In the course of this motion one of said pins will move outwardly, thereby removing its shoulder 145 as a barrier to the motion of said tread-plate; and the shoulder 145 of the other of said pins will contact that face 153 of the tread-plate 6 which is contiguous thereto, thereby pushing said tread-plate 6 before it. In the course of said motion the tread-plate 6 carries with it the wedge 43 which is finally caused to assume the position shown in Figures 5 and 6. The full and dot and dash lines in Figure 17 portray the respective movements of one of the pins and of the tread-plate in the making of such an adjustment.

In this case the wedge 43 fell between the rollers 44 and 47 with the face 45 out of contact and to the right of the roller 44. To secure such contact it was therefore necessary to move the wedge towards the left. The threaded pin 17 at the left side of the tread portion 2 was therefore screwed outwardly (toward the left) and moved from its full line position shown in Figure 17 to its dot and dash line position in said figure. Thereafter, the threaded pin 17 at the right side of the tread portion 2 was screwed inwardly (toward the left) a distance equal to that which the pin on the left side was moved outwardly. In the course of this motion, the shoulder 145 of the right hand pin contacted the face 153 of the tread-plate 6 which was contiguous thereto and pushed the plate 6 toward the left from its position designated by the full lines of the fragment shown in Figure 17 to that shown by the dot and dash lines in said figure. When the tread-plate reached the position designated by the dot and dash lines in Figure 17 the wall 45 contacted the roller 44.

It is further to be noted that the cable 56 may develop some slackness in use. Such slack is readily eliminated by advancing the bolt 51 the necessary distance.

It is further to be noted that in assembling the unit it may be necessary or desirable to make some major or minor adjustment either in the total length of the hollow standard 59 or in the angle which the guide slot 151 formed in the pulley 60 makes with any given base line. (Compare the angle formed in Figure 2 by the guide slot 151 and the edge of the plate 65 contiguous thereto with the angle formed by these elements in Figure 14.) To provide for such adjustments, the hollow standard 59 comprises the shaft 145,

the tube 146 which telescopes over the upper end of the shaft 145, and the tube 147 which telescopes over the lower end of the shaft 145. The tubes 146 and 147 are each laterally movable upon said shaft 145 and are also rotatable thereon. The tube 146 carries the pulley 60 and is locked in the desired position upon the shaft 145 by means of the set screw 148. The tube 147 carries the pulley 58 and is locked in the desired position by the set screw 149.

Although the operation of my device is believed to be obvious from the drawings and foregoing description, yet to obviate any possibility of a misunderstanding the following detailed description is here given.

Let it be assumed that the door 110 is closed and that a person is desirous of causing the same to open. As he moves toward the door 110 he steps upon the tread-plate 6. His weight exerts a force upon the tread-plate 6 in the direction of the arrow A in Figure 7, which is greater than the force exerted by the spring 122 upon the cam band 84. As a result, the tread-plate 6 moves downwardly about its pivots 7 and carries the wedges 43 and 49 downwardly with it. In the downward motion of the wedge 43 its surface 45 contacts and exerts pressure upon the roller 47 and in the downward motion of the wedge 49 its surface 50 contacts the roller 48. This results in the action of a couple upon the arm 8 causing it to move from its full line position in Figure 1 to its dot and dash line position in said figure. This results in the movement of the cable 56 which in turn causes the lever arm 74 to move in the direction of the arrow C in Figures 2 and 12. This results in the movement of the gear 78 in the direction of the arrow D, of the gear 79 in the direction of the arrow E, of the gear 80 in the direction of the arrow F, of the rack 82 in the direction of the arrow G, of the band 84 in the direction of the arrow H. At the beginning of this motion, the rack 82 and the cam band 84 move from their respective full and dotted line positions in Figure 12 to their respective dot and dash line positions in said figure. When the cam band 84 reaches its dot and dash line position in Figure 12, its surface 132 contacts and exerts pressure upon the roller 92 carried by the lever arm 90 urging the lever arm 90 of the lever 88 in the direction of the arrow I. This results in the rotation of the lever 88 about its pivot 93 in the direction of the arrow J. This results in the movement of the arm 94 of the lever 88 in the direction of the arrow K. This motion is communicated to the collar 97 through the socket 95 and the pin 96. This results in a contact between the side 134 of the lever arm 99 with that surface of the collar 97 adjacent to said side. This results in a pressure upon the lever arm 99 in the direction of the arrow L. This causes the rotation of the lever 88 about its pivot 101 in the direction of the arrow M. In moving in the direction of the arrow L, the arm 99 carries with it the socket pin 104. The socket pin 104 communicates this motion to the collar 105 through the pin 106. This causes the collar 105 to exert pressure upon the side 136 of the bar 107 in the direction of the arrow N. This in turn causes the door 110 to open by rotating in the direction of the arrow O about its hinges 138. As the door 110 continues to open, the collar 105 contacts the collar 115 and causes it to move in the direction of the arrow P which in turn causes the spring 112 to become compressed. The spring 112 acts as a shock absorber and also as a re-

tarder to slow down and limit the motion of the door 110.

When the person steps off the tread-plate 6, the force which he exerted in the direction of the arrow A (Figure 7) is removed. The pull of the extended spring 122 then becomes the strongest force in the door actuating mechanism 4. As a result, all of the movements hereinabove specified are reversed and the door 110 caused to close. In doing so, the cam band 84 and its associated elements move from their respective full line positions shown in Figure 13 to their respective full line positions shown in Figure 12, and the cable 56 and arm 8 move from their respective dot and dash line positions in Figure 1 to their respective full line positions in said figure. This permits the springs 35 to force the tread-plate 6 to rotate about its hinges 7 and rise from its depressed position to its normal position shown in Figures 1 and 7 of the drawings.

In the first phase of the movements aforesaid, the cam band 84 moves from its full line position shown in Figure 13 to its dot and dash line position in said Figure 6. In doing so, the outer face 132 of the cam band 84 ceases to contact the roller 92 carried on the lever arm 98 while the inner face 133 of said cam band 84 comes into contact with the roller 91 carried by the lever arm 89. This removes the pressure on the lever 88 causing it to rotate in the direction of the arrow J in Figure 2 and results in a pressure upon the lever 88 causing it to rotate in the direction of the arrow Q in Figure 13. This in turn results in the movement of the lever arm 94 in the direction opposite to the arrow K. This motion is communicated to the collar 97 and results in a contact between the side 135 of the lever arm 99 and that surface of the collar 97 adjacent to said face. This results in a pressure upon the lever arm 99 in a direction opposite to the arrow L. This causes the rotation of the lever 98 about its pivot 101 in the direction of the arrow R in Figure 13. In the course of this rotation, the lever arm 99 carries with it the socket pin 104 which communicates its motion to the collar 105. This causes the collar 105 to exert pressure upon the side 137 of the bar 107 in a direction opposite to the arrow N. This in turn causes the door 110 to close by moving about its hinges 138 in the direction opposite to the arrow O. It is to be noted that at certain points during the opening and closing of the door 110, the roller 103 comes into a position where it contacts the door 110. During the motion of closing the door, this contact produces a force on the door 110 in the direction of the arrow N. In the act of closing the door 110, this contact does not result in any appreciable force which retards the motion of the door 110 to its closed position. This is because the lever 99 is constantly being urged in the direction opposite to the arrow N during the time that the door 110 is being closed.

While the cam band 84 is exerting the pressure upon the roller 91 which results in the closing of the door 110, the rack 83 moves in the direction of the arrow S shown in Figure 13. This results in motions in the gears 80, 79, and 78 in the lever 74, and in the cable 56 in the direction of the arrows T, U, V, W, and X, respectively. This results in a pull upon the arm 9 causing it to move from its dot and dash line position to that shown by the full lines in said figure. This is readily accomplished because the springs 34 have already caused the tread-plate 6

to return from the depressed position to its normal position.

The door actuating portion 141 shown in Figures 14 and 15 differs from the door actuating mechanism 4 shown in Figures 1 to 4 and 12, 13 and 16 only in the following particulars:

(1) The gears 79 and 80 have been eliminated.

(2) The rack 142 has been substituted for its equivalent, 83.

(3) The rack 142 meshes directly with the gear 143 which otherwise is the equivalent of the gear 78.

(4) The lever 144 has been substituted for its equivalent, the lever 74.

(5) The tube 146 of the hollow standard 59 has been rotated from the position shown in Figures 1 and 2 to that shown in Figure 14. In the course of this rotation, the tube 146 has carried the pulley 60 from its position shown in Figures 1 and 2 to that shown in Figure 14.

The door actuating portion 141 may be substituted in my novel mechanism for the door actuating portion 4, particularly in cases where the door 110 is comparatively light. With the exception of the fact that there is a direct contact between the rack 142 and the gear 143 and therefore a direct transfer of force from each of said elements to the other, the unit which has a door actuating portion 141 as a component part functions exactly in the same manner as the unit which has a door actuating portion 4 as a component part.

The foregoing description is to be understood as being by the way of illustration only and not by the way of limitation since many changes may be made in the disclosure here made without departing from the spirit of my invention. These changes may include, among other things, changes in the shape and size of the various component elements of my mechanism and changes in the material of which said elements are made.

Having described my invention, what I claim as new and useful is:

1. A door opening device consisting of a base member; a tread-plate pivotally mounted in said base member; a door actuating portion positioned for operative contact with the door which is to be opened by said door opening device, said door actuating portion comprising a bar carried by said door, sliding means mounted for movement upon said bar, an arm pivoted near one of its ends and attached to said sliding means near the other of its ends, sliding means mounted for movement upon said arm, a second arm pivoted intermediate its ends and attached to said arm carried sliding means near one of its ends, a pair of spaced apart cam contacting members carried by said second arm, a cam band pivoted near one of its ends and positioned for contacting one of said cam contacting surfaces and exerting a force upon said bar mounted sliding means in the direction necessary to open said door when a person steps upon said tread-plate, and for contacting the other of said cam contacting surfaces and exerting a force upon said bar mounted sliding means in the direction necessary to close said door when said person steps off said tread-plate; and means operatively connecting said cam band with said tread-plate.

2. A door opening device consisting of a base member; a tread-plate pivotally mounted in said base member; a door actuating portion positioned for operative contact with the door which is to be opened by said door opening device, said

door actuating portion comprising a bar carried by said door, sliding means mounted for movement upon said bar, an arm pivoted near one of its ends and attached to said bar mounted sliding means at the other of its ends, sliding means mounted for movement upon said arm, a second arm pivoted intermediate its ends and attached to said arm mounted sliding means near one of its ends, two spaced apart cam contacting surfaces positioned upon said second arm intermediate its pivot point and its free end, a cam band pivoted near one of its ends and positioned intermediate said cam contacting surfaces for contacting one of said cam contacting surfaces and exerting a force upon said bar mounted sliding means in the direction necessary to open said door when a person steps upon said tread-plate and for exerting a force upon said bar mounted sliding means in the direction necessary to close said door when said person steps off said tread-plate; and means operatively connecting said cam band with said tread-plate.

3. A door opening device consisting of a base member; a tread-plate pivotally mounted in said base member and movable therein to assume either a raised or a lowered position; an arm mounted for movement beneath said tread-plate; means carried by said tread-plate and positioned for contacting said arm and exerting a force on said arm when said tread-plate is being moved toward its lowered position; a door actuating portion positioned for operative contact with the door which is to be opened by said door opening device, said door actuating portion comprising a bar carried by said door, sliding means mounted for movement upon said bar, an arm pivoted near one of its ends and attached to said bar mounted sliding means at the other of its ends, sliding means mounted for movement upon said arm, a second arm pivoted intermediate its ends and attached near one of its ends to said arm mounted sliding means, two spaced apart cam contacting surfaces positioned upon said second arm intermediate its pivot point and its free end, a cam band pivoted near one of its ends and positioned intermediate said cam contacting surfaces for contacting one of said cam contacting surfaces and exerting a force upon said bar mounted sliding means in the direction necessary to open said door when a person steps upon said tread-plate and for exerting a force upon said bar mounted sliding means in the direction necessary to close said door when said person steps off said tread-plate; and means operatively connecting said arm mounted beneath said tread-plate with said cam band.

4. A door opening device consisting of a base member; a tread-plate mounted in said base member and movable therein to either a raised or lowered position; resilient means positioned in said base member, contacting said tread-plate and exerting a force on said tread-plate sufficient to hold said tread-plate in its raised position; an arm pivoted intermediate its ends and positioned beneath said tread-plate; a wedge carried by said tread-plate and positioned for contacting one of the faces of said arm; a second wedge carried by said tread-plate and positioned for contacting that face of said arm opposite to that which is contacted by the first of said wedges and on that side of the pivot point which is opposite to that which is contacted by the first of said wedges; a door actuating portion positioned for operative contact with the door which is to be opened by said door opening de-

vice, said door actuating portion comprising a bar carried by said door, sliding means mounted for movement upon said bar, a base plate, an arm pivoted near one of its ends in said base plate and attached to said bar mounted sliding means at the other of its ends in said base plate and attached near one of its ends to said arm mounted sliding means, two spaced apart cam contacting surfaces positioned upon said second arm intermediate its pivot point and its free end, a cam band pivoted near one of its ends and positioned intermediate said cam contacting surfaces for alternately contacting each of said cam contacting surfaces, means attached to said cam band for exerting a force on said cam band in the direction necessary to cause said cam band to contact one of said cam contacting surfaces and to exert a force upon said bar mounted sliding means in the direction necessary to close said door, and a second means operatively connecting said cam band with said arm positioned beneath said tread-plate for exerting a force on said cam band in the direction necessary to cause said cam band to contact the other of said cam contacting surfaces and exert a pressure upon said bar mounted sliding means in the direction necessary to open said door when a person steps upon said tread-plate.

5. A door opening device comprising means mounted for sliding movement upon the door which is to be opened; an arm pivoted at a point intermediate its ends; means operatively connecting said pivoted arm with said sliding means; a pair of spaced apart cam contacting surfaces pivotally mounted on said arm; a cam band pivoted near one of its ends and extending between said cam contacting surfaces; cam band actuating means operatively connected with said cam band for exerting a force upon said cam band in the direction necessary to cause said cam band to contact one of said cam contacting surfaces and exert a force upon said door mounted sliding means in the direction necessary to open said door; and a second cam band actuating means operatively connected with said cam band and exerting a force upon said cam band in the direction necessary to cause said cam band to contact the other of said cam contacting surfaces and exert a force upon said door mounted sliding means in the direction necessary to close said door.

6. A door opening device comprising a bar carried by the door which is to be opened; sliding means mounted for movement upon said bar; a supporting member; an arm pivoted near one of its ends in said supporting member and attached to said sliding means near the other of its ends; sliding means mounted for movement upon said arm; a second arm pivoted intermediate its ends in said supporting member and attached to said arm carried sliding means near one of its ends; a pair of spaced apart cam contacting members carried by said second arm; a cam band pivotally mounted in said supporting member and extending between said cam contacting surfaces; cam band actuating means operatively connected with said cam band for exerting a force upon said cam band in the direction necessary to cause said cam band to contact one of said cam contacting surfaces and exert a force upon said door mounted sliding means in the direction necessary to open said door; and a second cam band actuating means operatively connected with said

cam band and exerting a force upon said cam band in the direction necessary to cause said cam band to contact the other of said cam contacting surfaces and exert a force upon said door mounted sliding means in the direction necessary to close said door.

7. A door opening device comprising means mounted upon the door which is to be opened for alternately exerting a force upon said door either in the direction necessary to open or in the direction necessary to close said door; an arm pivoted at a point intermediate its ends; means operatively connecting said pivoted arm with said door mounted means; a pair of spaced apart cam contacting surfaces pivotally mounted on said arm; a pivotally mounted cam band extending between said cam contacting surfaces; cam band actuating means operatively connected with said cam band for exerting a force upon said cam band in the direction necessary to cause said cam band to contact one of said cam contacting surfaces and exert a force upon said door mounted means in the direction necessary to close said door.

8. An element of an automatic door opening device, said element comprising sliding means which is attached to the door which is to be opened; a supporting member; an arm pivoted near one of its ends in said supporting member and attached to said sliding means near the other of its ends; sliding means mounted for movement upon said arm; a second arm pivoted intermediate its ends in said supporting member and attached to said arm carried sliding means near one of its ends; a pair of spaced apart cam contacting members carried by said second arm; a cam band pivotally mounted in said supporting member and extending between said cam contacting surfaces; cam band actuating means operatively connected with said cam band and exerting a force upon said cam band in the direction necessary to cause said cam band to contact one of said cam contacting surfaces and exert a force upon said sliding means in the direction necessary to close said door; and means operatively connected to said cam band for connecting said cam band to a source of power.

9. A door opening device comprising a base member; a tread plate pivotally mounted in said base member; a door actuating portion positioned for operative contact with the door which is to be opened by said door opening device, said door actuating portion comprising a bar which is connected to said door, sliding means mounted upon said bar, a pair of spaced apart cam contacting members operatively connected to said sliding means, a cam band extending between said cam contacting members and positioned for contacting one of said cam contacting members and exerting a force upon said sliding means and cause said sliding means to move in the direction necessary to open said door when a person steps upon said tread plate and for exerting a force upon said sliding means and cause said sliding means to move in the direction necessary to close said door when said person steps off said

tread plate; and means operatively connecting said cam band with said tread plate.

10. A door opening device comprising a base member; a tread plate movably mounted in said base member; a door actuating portion positioned for operative contact with the door which is to be opened by said door opening device, said door actuating portion comprising a bar which is connected to said door, sliding means mounted upon said bar, an arm operatively connected to said sliding means, a second arm operatively connected to said first arm, a pair of spaced apart cam contacting members carried by said second arm, a cam band extending between said cam contacting members and positioned for contacting one of said cam contacting members and exerting a force upon said sliding means through said second and first arms and cause said sliding means to move in the direction necessary to open said door when a person steps upon said tread plate, and for contacting the other of said cam contacting members and exerting a force upon said sliding means through said second and first arms and cause said sliding means to move in the direction necessary to close said door when a person steps off said tread plate; and means operatively connecting said cam band with said tread plate.

11. An element of an automatic door opening device, said element comprising sliding means which is attached to the door which is to be opened; a supporting member; an arm pivoted in said supporting member at a point intermediate its ends; a pair of spaced apart cam contacting members pivotally mounted in said arm; means operatively connecting said arm with said sliding means; a cam band pivotally mounted in said supporting member and extending between said cam contacting surfaces; cam band actuating means operatively connected with said cam band and exerting a force upon said cam band in the direction necessary to cause said cam band to contact one of said cam contacting surfaces and exert a force upon said sliding means in the direction necessary to close said door; and means operatively connected to said cam band for connecting said cam band to a source of power.

12. An element of an automatic door opening device, said element comprising means mounted upon the door which is to be opened for alternately exerting a force upon said door either in the direction necessary to open or in the direction necessary to close said door; a supporting member; an arm pivoted in said supporting member at a point intermediate its ends; a pair of spaced apart cam contacting members pivotally mounted in said arm; means operatively connecting said arm with said door mounted means; a cam band pivotally mounted in said supporting member and extending between said cam contacting surfaces; cam band actuating means operatively connected with said cam band and exerting a force upon said cam band in the direction necessary to cause said cam band to contact one of said cam contacting surfaces and exert a force upon said door mounted means in the direction necessary to close said door; and means operatively connected to said cam band for connecting said cam band to a source of power.

ROBERT HASLAM.
